UNITED STATES PATENT OFFICE

148,778

DESIGN FOR A CAMERA TRIPOD HEAD OR SIMILAR ARTICLE

Jacob Franz Fishter, Santa Monica, Calif., assignor to Panogear Industries, Los Angeles, Calif., a corporation of California

Application May 12, 1947, Serial No. 138,984

Term of patent 14 years

(Cl. D61—1)

To all whom it may concern:

Be it known that I, Jacob Franz Fishter, a citizen of the United States, residing at Santa Monica, in the county of Los Angeles and State of California, have invented a new, original, and ornamental Design for a Camera Tripod Head or Similar Article, of which the following is a specification, reference being had to the accompanying drawings, forming a part thereof.

Figure 1 is a view in front elevation of a camera tripod head, illustrating my new design.

Figure 2 is a side elevation taken in the direction of the arrow 2 in Figure 1.

Figure 3 is a rear elevation taken in the direction of the arrow 3 in Figure 2.

Figure 4 is a side elevation taken in the direction of the arrow 4 of Figure 1.

I claim:

The ornamental design for a camera tripod head or similar article, substantially as shown.

JACOB FRANZ FISHTER.
